UNITED STATES PATENT OFFICE.

THOMAS E. BARNUM, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,265,727.

Specification of Letters Patent.

Patented May 14, 1918.

Application filed April 8, 1916. Serial No. 82,859.

To all whom it may concern:

Be it known that I, THOMAS E. BARNUM, a citizen of the United States, residing at Milwaukee, in the county of Milwaukee and 5 State of Wisconsin, have invented new and useful Improvements in Circuit-Controllers, of which the following is a full, clear, concise, and exact description, reference being had to the accompanying drawing, forming 10 a part of this specification.

This invention relates to circuit controllers and more particularly to contact supporting means therefor.

One of the objects of the invention is to 15 provide contact supporting means of simple and inexpensive construction which will provide for firm support of the one or more contacts carried thereby and which will provide for expeditious and easy mounting of 20 such contacts.

A further object is to provide supporting means readily adaptable to alternative types of contacts.

Other objects will hereinafter appear. 25 The accompanying drawing illustrates a controller embodying the invention and the same will now be described, it being understood that the invention is susceptible of embodiment in other forms falling within 30 the scope of the appended claims.

In the drawing,

Figure 1 is a partial sectional view of the drum controller with the drum merely shown in broken lines; and,

35 Fig. 2 is a similar view showing the contact supporting means adapted to an alternative type of contact.

Referring to Fig. 1, the controller comprises a rotary contacting drum 1 arranged 40 to coöperate in the usual manner with a plurality of relatively fixed contact fingers 2 (only one of which is illustrated) each finger being carried by a bracket 3 mounted upon a fixed base or support 4 and insulated 45 therefrom, and all of the above parts being inclosed in a suitable casing 5.

The base is fixed in parallel relation to the drum 1 and at right angles to its direction of movement, and is formed polygonal in 50 cross section. The bracket 3 is correspondingly shaped to fit around said base and comprises sections 6 and 7. The bracket section 6 comprises a flat plate bent to the proper angle and having one leg thereof 55 crimped to form a socket or pivot bearing

8 for the contact finger 2 of conventional form, said leg having also an offset extremity 9 forming a stop for said finger. The other leg of said section is left flat. The bracket section 7 which is similarly bent 60 and provided with an angularly offset extremity 10 supplements the section 6 in circumengaging the base 4 and said sections are clamped thereabout by bolts 11 and 12. The bolt 11, in addition to its clamping 65 function, is properly located and proportioned to constitute a stem for a conventional tensioning device 13 for the finger 2, while the bolt 12 is extended to form a binding post for a terminal lug 14. The bracket 70 also serves to support an insulating plate 15 to shield the same from arcs drawn by the drum 1, said plate being recessed to receive the bracket extremity 9 for support at one end and being secured at its opposite 75 end to bracket extremity 10 by a screw 16.

The arrangement shown in Fig. 2 employs the same bracket for an alternative type of contact. The bracket is, however, shifted about the base to present the flat 80 portion 17 thereof in proper relation for supporting the alternative form of contact finger 2' which is mounted upon a plate 18 riveted to said portion of the bracket. In this construction the shield 15 and the offset 85 extremity 9 are omitted, while the supplemental bracket section 7 is reversed endwise, the relation and co-action of parts being otherwise the same as in the preceding 90 figure.

Obviously the above described supporting bracket is capable of ready and facile attachment or detachment and is further adapted to be readily shifted with respect to its base to accommodate either of the 95 alternative types of contact finger shown. It is further obvious that the said bracket may be readily adapted to types of contact finger other than those disclosed. The construction, moreover, is simple and rugged 100 and well adapted by its location and arrangement to resist the strains incidental to use.

What I claim as new and desire to secure by Letters Patent is:

1. Contact supporting means for circuit controllers, comprising a base and a bracket having means to secure the same to said base, said bracket having mounting parts for alternative forms of contacts and be- 110

ing adjustable with respect to said base for positioning either of said mounting parts in a given relation with respect to said base.

2. Contact supporting means for circuit controllers comprising a base of polygonal cross section and a contact supporting bracket of corresponding polygonal formation to fit about and clamp upon said member, said bracket having mounting parts for alternative forms of contacts and being shiftable about said supporting member to position either of said mounting parts in a given relation with respect to said base.

3. Contact supporting means for circuit controllers comprising a supporting base, bracket sections to surround said base, one of said bracket sections having a bearing part and a stop part for the contact to be attached thereto and bolts securing said bracket sections together in a clamped relation upon said base, one of said bolts being extended to provide a stem for a tension device for the contact to be attached thereto.

25 4. In a circuit controller, in combination, a contact member, a supporting base, a sectional bracket to be clamped upon said base, said bracket providing a bearing for said contact member and securing bolts for the sections of said bracket serving to clamp the same upon said base, one of said bolts being extended and said contact member having a tensioning device mounted upon said extended bolt.

35 5. A contact supporting bracket comprising angle plates one having a contact mounting part and each having a part to form with that of the other a mounting for an insulating shield and means for securing said plates together and clamping the same upon a suitable support.

6. Contact supporting means for circuit controllers comprising a supporting base and a contact carrying bracket comprising coöoperating sections circumengaging said

base, one section having a contact mounting part and each section having a part to form with that of the other a mounting for an insulating shield and bolts for said sections serving to clamp the same firmly upon said base.

7. Contact supporting means for circuit controllers comprising a supporting base and a contact carrying bracket the former being polygonal in cross section and the latter comprising angular sections surrounding said base and bolts for said sections serving to firmly clamp the same upon said base, one of said bolts being extended to provide a stem for a tension device for the contact to be attached thereto and another of said bolts being extended to provide a binding post.

8. Contact supporting means for circuit controllers comprising a supporting base and a contact carrying bracket comprising coöoperating sections circumengaging said base, one section having a contact mounting part and each section having a part to form with that of the other a mounting for an insulating shield and bolts for said sections serving to clamp the same firmly upon said base, one of said bolts being extended to form a stem for a tension device for the contact to be attached thereto.

75 9. In a circuit controller, in combination, a contact member, a supporting base, a sectional bracket to be clamped about said base, one section of said bracket having a bearing mounting and a stop for said contact, said sections having parts jointly constituting a support for an insulating shield, said bracket being further provided with a part for mounting an alternative form of contact and being readily shiftable with respect to said base for positioning of said last mentioned part.

In witness whereof, I have hereunto subscribed my name.

THOMAS E. BARNUM.
